TWO-CYCLE DIESEL ENGINE

James A. Eaton, Birmingham, Mich., assignor to
Francie Eaton, Birmingham, Mich.

Application April 20, 1939, Serial No. 268,897

1 Claim. (Cl. 123—57)

This invention appertains to two-cycle Diesel engines of the type having opposed pistons, and is an improvement over my prior Patent No. 2,147,644, of February 21, 1939.

One of the primary objects of my invention is to provide an engine of the above character which is of a powerful, yet light and rugged, character, whereby the same can be successfully used in the automotive field.

Another salient object of my invention is to provide an engine having a cylinder head cast "en bloc" for the aligned cylinders, whereby to facilitate placing of the head in position, and whereby to further facilitate the connection of the water cooling and circulating pipes with all of the cylinders.

A further important object of my invention is the provision of a novel arrangement of cylinders and cylinder head, whereby not only can all of the parts be conveniently connected, but whereby the fuel pump, air blower, etc., can be conveniently arranged relative to the engine.

A still further important object of my invention is the provision of a trunk-type piston in each cylinder for controlling the inlet of the air to the cylinder, and the scavenging of the burnt charge from the cylinder, with novel means for forming the piston head, whereby to facilitate the sweeping of the air through the cylinder for scavenging purposes, and whereby to assure a turbulence within the cylinder, so that the air will be thoroughly mixed with the injected fuel.

With these and other objects in view, the invention consists in the novel construction, arrangement, and formation of parts, as will be hereinafter more specifically described, claimed, and illustrated in the accompanying drawings, in which drawings:

Figure 1 is a top plan view of my improved engine, showing parts thereof removed and broken away, so as to illustrate structural details.

Figure 2 is a longitudinal sectional view through the engine, taken on the line 2—2 of Figure 1, looking in the direction of the arrows.

Figure 3 is an enlarged, transverse, sectional view through the engine, taken on the line 3—3 of Figure 2, looking in the direction of the arrows, and illustrating the novel cylinder head.

Figure 4 is a fragmentary, side elevational view of one of the pistons, the view being at right angles to Figure 2.

Referring to the drawings in detail wherein similar reference characters designate corresponding parts throughout the several views, the 55

letter E generally indicates my novel two-cycle Diesel engine, and the same embodies a plurality of spaced pairs of longitudinally aligned cylinders 5. In the present instance I have shown three pairs of cylinders, and, hence, a six-cylinder engine will be illustrated.

All of the cylinders 5 are preferably water-jacketed, as at 6, so as to facilitate the proper cooling thereof, and each of the cylinders, at a point intermediate its ends, is provided with an air inlet port 7 and an exhaust port 8. The ports 7 and 8 are diametrically opposite on another, and the ways 9 and 10 leading to said ports are preferably inclined toward the inner ends of the cylinders, for a purpose which will be later set forth. Trunk pistons 11 are reciprocally mounted within the cylinders, and these pistons are fitted at the appropriate points with rings 12 for sealing the compression in the cylinders and for preventing the leakage of oil past the pistons. The inner ends of the pistons terminate in V-shaped extensions 13, which cooperate with the inclined ways 9 and 10 for facilitating the scavenging of the spent charge from the cylinders.

The aligned cylinders have their inner ends arranged in spaced relation, and a cylinder head 14 is adapted to be placed between the inner ends of the aligned cylinders. The cylinder head 14 can be cast "en bloc," and is, likewise, provided with a cooling water chamber 15. This water chamber 15 communicates with the water jackets 6 of the various cylinders through water ports 16 formed in the cylinder head and the cylinders. Communicating with the water chamber 15 of the cylinder head 14 is a water-conducting circulating pipe 17. The cylinder head for each cylinder has a laterally offset chamber 18 in which is fitted the fuel injection valve 19.

By referring to Figure 3, it can be seen that the V-shaped extensions 13 of the pistons are adapted to protrude into the cylinder heads, and, thus, the charge is highly compressed between the V-shaped extensions of the pistons and the cylinder heads.

The outer ends of the pistons have their skirts provided with flanges 20, and these flanges are connected by tie rods 21. The tie rods 21 are efficiently guided during the reciprocation of the pistons, so that the pistons will be held in line, and so that wear will be reduced between the pistons and the cylinder walls. Thus, the outer faces of the cylinders, at spaced points, are provided with bearings 22 for the rods. These bearings 22 have removable bearing caps 23, whereby the liners for the bearings can be conveniently

renewed when worn. As is clearly shown in Figure 3, four connecting rods are utilized for connecting each pair of pistons together, and each cylinder carries four bearings, making eight bearings in all for each four guide rods.

The cylinders are firmly united to the cylinder heads 14, and the piston heads at appropriate points can be provided with laterally extending ears 24 through which extend coupling bolts 25. Again referring to the tie rods 21, it will be noted that the bearings have associated therewith guide sleeves 26 for encompassing the tie rods. Thus, the tie rods for the entire portion of their lengths are enclosed and lubricated.

The pistons 11 at one end of the engine carry wrist-pins 27 on which are rockably mounted the connecting rods 28. The connecting rods 28 are operatively connected to the throws or arms 29 of the crank-shaft 30. The crank-shaft 30 is of the balanced type and is supported in the desired number and type of bearings. A crank-case 31 is bolted to the cylinders at one end for housing the crank-shaft, and the crank-case can be made in sections, so as to facilitate the entrance to the crank-shaft when such is desirable.

The cylinders at the other end of the engine can, likewise, be encased in a suitable sectional case 32, and this case 32 is also bolted to the cylinders. Any desired means is employed for delivering oil to the cases 31 and 32, and I prefer to connect the cases by an oil connecting pipe 33.

The crank-shaft 30 at one end can be provided with a balance wheel 34 and a drive pulley wheel 35. The other end of the crank-shaft can have keyed or otherwise secured thereto a beveled gear wheel 36.

The various appurtenances for the engine can be driven from the crank-shaft, such as water pumps, air circulating fans, air blowers, fuel pumps, etc. In the present instance, I have shown an air blower 37 disposed at one side of the engine, and this blower is driven by a belt 38 from the pulley 35. The outlet of the blower 37 communicates with a manifold pipe 39, the branches of which lead to the inlet openings 7. The exhaust openings 8 and the exhaust passage-ways 10 have communicating therewith the branches of the exhaust manifold 40.

On the opposite side of the engine from the blower 37 I arrange any preferred type of fuel pump and distributor 41, and this pump and distributor can be driven from a shaft 42, and the shaft 42, in turn, can be operated from the beveled gear 36. The fuel pump and distributor are provided with a plurality of fuel-conducting pipes 43, which lead to the injector nozzles 19.

In operation of my engine, each piston compresses the air to practically its full compression, plus or minus 500 lb. per square inch, or until the crank reaches a point 12% or 15% of its top dead center (according to the speed of the engine). At this time, the fuel oil is injected into the compressed air in the cylinder under a pres-

sure ranging from 3500 lb. to 6000 lb. per square inch, which atomizes the fuel oil in the compressed air. The compressed air at 500 lb. pressure in one stroke raises the temperature of the air to practically 1000° Fahrenheit, which heat will instantly ignite the fuel charge. The pistons will be driven to the outer end of the cylinders. As the piston uncovers the ports 7 and 8, air from the blower will be forced under pressure through the port 7, and as the air rides through the inclined way 9, the same will be directed across the cylinder and toward the cylinder head, and, thus, this air will sweep through the cylinder, back toward the exhaust port 8, carrying all of the burnt gasses through the inclined way 10 and into the exhaust manifold. This fresh air will be compressed between the piston and the cylinder, as the piston head again moves toward the cylinder head and closes the ports 7 and 8. At this time, fuel is injected into the cylinder under high pressure, and the air stream in the cylinder will combine with the fuel under pressure, and as the piston reaches the end of its stroke, the charge will again be fired.

Great stress is laid on the V-shape of the piston, as on the pressure stroke, as the piston moves toward the cylinder head, the air impinging against the inclined faces will be directed toward the opposite sides of the cylinders in moving paths, and, thus, the turbulence within the cylinder will be increased. On the discharge stroke of the piston the incoming air will strike the inclined face of the piston, and the face of the piston in conjunction with the inclined way 9 serves to guide the air across the piston toward the piston head, and then back to the inclined way 10 of the exhaust port.

Changes in details may be made without departing from the spirit or the scope of my invention, but what I claim as new is:

In a Diesel two-cycle engine, a unit comprising, a pair of longitudinally aligned cylinders, a cylinder head connecting said cylinders and occupying the space therebetween, each having an offset chamber, a fuel injector nozzle arranged in each chamber, pistons reciprocally mounted in the cylinders, means operatively connecting the pistons together, a crank-shaft, connecting rods operatively connecting the crank-shaft to certain of the pistons, V-shaped extensions formed on the inner ends of the pistons adapted to ride into the cylinder head, each of the cylinders having diametrically opposite inclined inlet and outlet ports arranged intermediate their ends leading toward the cylinder heads adapted to be covered and uncovered by the pistons, a blower communicating with the inlet ports, and an exhaust manifold communicating with the outlet ports, said ports having inclined ways extending toward the cylinder heads, the inclined sides of the V-shaped piston extensions inclining toward said inclined inlet and outlet ports.

JAMES A. EATON.
